US0D1100910S

(12) **United States Design Patent** (10) Patent No.: **US D1,100,910 S**
(45) Date of Patent: ** Nov. 4, 2025

(54) **DATA PROCESSING SCANNER**

(71) Applicant: **Orbbee Inc.**, Shenzhen (CN)

(72) Inventors: **Chaojun Peng**, Guangdong (CN);
Yuhua Xu, Guangdong (CN);
Guoshuai Liu, Guangdong (CN)

(**) Term: **15 Years**

(21) Appl. No.: **35/521,542**

(22) Filed: **Jun. 18, 2024**

(80) **Hague Agreement Data**

Int. Filing Date: **Jun. 18, 2024**

Int. Reg. No.: **DM/238062**

Int. Reg. Date: **Jun. 18, 2024**

Int. Reg. Pub. Date: **Jul. 5, 2024**

(30) **Foreign Application Priority Data**

Feb. 7, 2024 (CN) 202430082640.6

Primary Examiner — George A Bugg

Assistant Examiner — Cole Sanders Holman

(57) **CLAIM**

The ornamental design for a data processing scanner as shown and described.

DESCRIPTION

1.1: Perspective

1.2: Front

1.3: Back

1.4: Left

1.5: Right

1.6: Top

1.7: Bottom

The broken lines depict portions of the data processing scanner which form no part of the claimed design.

1 Claim, 7 Drawing Sheets
